UNITED STATES PATENT OFFICE.

GEORGE A. AMSDEN, OF LITTLETON, MASSACHUSETTS, ASSIGNOR TO THE LAMSON COMPANY, OF BOSTON, MASSACHUSETTS, A CORPORATION OF NEW JERSEY.

CARRIER FOR CABLE-CARRIER SYSTEMS.

1,258,385.

Specification of Letters Patent.

Patented Mar. 5, 1918.

Application filed July 20, 1914. Serial No. 851,879.

To all whom it may concern:

Be it known that I, GEORGE A. AMSDEN, a citizen of the United States, residing at Littleton, in the county of Middlesex and State 5 of Massachusetts, have invented certain new and useful Improvements in Carriers for Cable-Carrier Systems, of which the following is a specification.

This invention relates to carriers and more 10 especially to carriers for what is known as cable carrier apparatus. In my Patent No. 1,071,018, dated August 26, 1913, which relates to an improved locking device for carriers, I have shown a carrier which is not 15 dissimilar in many respects to that herein given by way of exemplification of my present invention; but I have now succeeded in improving my former construction, so that the locking device is very much more simple 20 and in certain ways even less subject to injury than is the device shown in said patent.

In fact, in the present case, the latch becomes peculiarly a part of the carrier for reasons hereinafter set forth.

25 In the accompanying drawing which forms a part hereof and in which like reference characters designate like parts throughout the several views, I have exemplified a preferred construction, but as I 30 am aware of various changes and modifications which may be made herein without departing from the spirit of my invention, I desire to be limited only by the scope of the claims appended hereto.

35 Referring to the drawing:

Figure 1 is a plan view of a cable carrier. Fig. 2 is a side elevation of said carrier. Fig. 3 is an end view of the same.

Fig. 4 is a bottom view of the carrier, and 40 Fig. 5 is a detail section taken on line V—V of Fig. 1.

The receptacle or body 1 of the carrier may be of sheet metal or other suitable material and if the carrier is designed for use in 45 a cable carrier system, the bottom of this receptacle preferably has secured thereto a fiber plate 2 which engages the rails or rods upon which the carrier travels.

A fiber block 3 serves to space the plate 2 50 away from the metal base 4 which may be provided with the usual lugs 5, which also engage the rails and retain the carrier in place thereon.

The block 3 is recessed for the reception 55 of the usual pivoted jaw 6 of the cable grip-

ping device, and the coöperating jaw 7 of this latter may, if desired, be fixed to the base plate 4, as by means of rivets 8 or the like. The pivoted stem 9 of the jaw 6 carries a prong or tooth 10 adapted for engagement with a spring 11, so that the jaw is normally held either in its open or closed position.

The spring 11 may be inclosed by an arcuate plate 12 which constitutes one portion of 60 the inner wall of the receptacle proper.

All of the above mentioned elements are common to devices of this character and hence need not be further herein described.

The receptacle is provided with a cover 70 or closure 13 which may be mounted upon a pin 14 and which is preferably given a tendency for movement to its open position by a spring 15, mounted upon the center of the pin 14 between the hinge parts 16 of the 75 cover. The cover carries, preferably upon its outer side, a latch 17 pivoted thereto at 18; said latch preferably consisting of a flat sheet metal strip, the free end 19 of which is bent up to form a handle for said latch. 80

When the latch is in its closed position, as shown in full lines in Figs. 1 and 2, this upturned flange or edge 19 is disposed in a recess 20 cut in the upper edge of the receptacle 1, and if the receptacle have a curved 85 surface, as it is preferably given for cable carriers, this flange may also be slightly arced to conform to the curvature of the box.

This construction renders the box very 90 slightly in appearance and very effectively protects the handle from injury or from inadvertently engaging some one of the operating parts of the cable system.

While in my said Patent No. 1,071,018, the latch was caused to engage with a projection upon the inner wall of the receptacle, herein a reverse construction is employed to advantage; since no such projection is present and thereby the contents of the box, especially if bulky, may be more readily introduced thereinto or removed therefrom; there being no projection in the wall to impede such actions.

Instead of a projection, in the present case, I have recessed or slotted the wall of 105 the receptacle as at 21, and a nose or preferably rounded point 22 upon the latch is adapted to enter and seat itself in this recess 21, as the latch is moved to its closed or locking position.

Thus the latch is enabled to effectively lock the cover against movement to its open position by its spring 15, or from other cause, while at the same time the carrier as a whole is improved both as regards accessibility to the receptacle space thereof, appearance and simplicity, while its cost of manufacture is materially reduced.

There is a decided advantage in cutting the slot entirely through the lateral wall of the receptacle, since if this be not done, dust or dirt is apt in time to accumulate in the recess and when the latter has become clogged up, the latch cannot well be fully closed; whereas if the slot extends entirely through the receptacle wall, any clogging substance is automatically swept or pushed out of the recess each time that the latch is moved into operative engagement with the receptacle.

It is desirable to provide a stop to limit the unlocking movement of the latch, and to this end a rivet 23 may be secured in the cover, against the head of which rivet the latch comes to rest, as shown by dotted lines in Fig. 1.

Friction may be relied upon to hold the latch in its closed position and as long as the carrier is new such means for preventing inadvertent opening of the cover may prove efficacious; but devices of this character are subject to rough usage, and after the latch has been operated a number of thousand times a mere clamping together into frictional engagement of the latch and cover cannot be relied upon.

I prefer, therefore, to indent or strike up the cover as at 24, so that this struck up portion will bear against the inner edge of the latch when the latter is in its closed position as shown in Fig. 1.

The latch, being of sheet metal, is sufficiently resilient to clear this obstruction when the handle-flange is pressed inwardly by the finger of the operator, and it is preferable, for this reason, to shape the struck up portion 24, as shown in Fig. 5, with sloping sides to facilitate the riding up thereupon of the shank of the latch.

If desired, this button, as we may term it, may also serve the additional function of maintaining the latch in its open position when moved thereinto, since the inner point of the handle 19, or some like portion, may bear against or be subject to contact with the button 24 when the latch is in its open position, as indicated by the dotted outline of the latch in Fig. 1.

It will be observed, therefore, that by virtue of the novel disposition of but few and very simple elements, a considerably improved locking device for carriers is provided.

In conclusion I particularly desire to point out the value of recessing the edge of

the receptacle wall, as at 20, for the reception and protection of the handle-flange of the latch, since while pressure upon the outer or exposed side of this flange suffices to effect an opening of the carrier, there need be absolutely no projection of any operating part of the locking device above the receptacle wall, and at the same time the box is exceedingly neat and attractive in appearance.

Having thus described my invention what I claim is:

1. A carrier receptacle having a closure, a spring acting to open said closure and means for resisting the action of said spring, said means including a latch lever one part of which is bent away from the closure to form a handle, said receptacle having a wall thereof recessed inwardly directly from the edge of the receptacle to form a pocket for the reception and protection of said handle.

2. A carrier receptacle having a closure, a spring acting to open said closure and means for resisting the action of said spring, said means including a latch lever one part of which is bent to form a handle, said receptacle having a wall thereof recessed for the reception and protection of said handle, and means for preventing inadvertent displacement of said handle from said recess.

3. A carrier receptacle having a closure, a spring acting to open said closure and means for resisting the action of said spring, said means including a lever, a latching part of which is disposed in a recess in a wall of said receptacle when said closure is locked, said lever having another part thereof also disposed in a recess in a lateral wall of said receptacle when said latching part is disposed in manner aforesaid.

4. A carrier receptacle having a closure, a spring acting to open said closure and means for resisting the action of said spring, said means including a latch element, a plurality of spaced apart parts of which are received into and protected by a wall of said receptacle when said lever is in its locking position.

5. A carrier having a hinged cover, a latch therefor pivoted upon the outer side of said cover where its movements cannot injure articles disposed in said carrier, a lateral wall of said carrier having a short slot therein for receiving and engaging a part of said latch to hold said cover closed, said carrier having a receptacle part adapted to be closed by said cover and the walls of said receptacle past which articles being inserted into or removed from said receptacle may slide, being substantially smooth and unbroken by projections which would interfere with the said insertion or removal of said articles.

6. A carrier having a hinged cover, a latch therefor having a resilient handle, and

a button on said cover over which said handle may be forced when being moved to its closed position, said button adapted to hold said latch against inadvertent displacement 5 either toward its open position when the cover is locked or toward its latching position when the cover is open.

7. A carrier having a hinged cover, a latch therefor having a resilient handle, and 10 a button on said cover over which said handle may be forced when being moved to its closed position, said button adapted to hold said latch against inadvertent displacement either toward its open position when the 15 cover is locked or toward its latching position when the cover is open, said button being struck up from the body of said cover.

8. A carrier having a hinged cover and a latch having a handle part pivoted to the outer side of said cover, said cover being set 20 into the body of the carrier when in its closed position so that the edge of the carrier protects both said cover and its latch, said body being also recessed in said edge for the reception of the latch handle, the 25 outer face of said handle being exposed through said recess to facilitate manipulation of said handle.

In testimony whereof I have affixed my signature, in the presence of two witnesses. 30

GEORGE A. AMSDEN.
